UNITED STATES PATENT OFFICE.

HERMAN F. BALL, OF BRONXVILLE, NEW YORK, ASSIGNEE TO ECONOMY DEVICES CORPORATION, OF NEW YORK, N. Y., A CORPORATION OF NEW YORK.

DRAW-BAR-PIN KEEPER.

1,236,366.

Specification of Letters Patent. Patented Aug. 7, 1917.

Application filed May 2, 1917. Serial No. 165,828.

To all whom it may concern:

Be it known that I, HERMAN F. BALL, of Bronxville, in the county of Westchester and State of New York, have invented a certain new and useful Improvement in Draw-Bar-Pin Keepers, of which improvement the following is a specification.

My invention relates to means for detachably connecting railroad vehicles, particularly to appliances of the type set forth in an application for Letters Patent filed by me February 27, 1917, Ser. No. 151,213, and its object is to provide simple and effective means for preventing the accidental dis- placement of drawbar pins in service.

The improvement claimed is hereinafter fully set forth.

In the accompanying drawings: Figure 1 is a vertical longitudinal central section 20 through a drawbar appliance, illustrating an application of my invention; and, Fig. 2, a vertical transverse section on the line $\alpha-\alpha$ of Fig. 1.

Under certain structural conditions, as in the case of tenders having water bottom tanks, and locomotives on which certain designs of stoking mechanism are applied, drawbar pins cannot be inserted from above the drawbar, and it therefore becomes necessary to adopt some means to prevent them, when inserted from below, from accidentally dropping down and out of the drawbar, and consequently inducing the separation of the locomotive and tender. My invention is designed to provide means, which will be readily applicable, at slight cost, in drawbar constructions of any of the ordinary forms, for preventing this objectionable result.

My invention is herein exemplified as applied in connection with a locomotive and tender connection of the type of that of my application Ser. No. 151,213 aforesaid, there being a main draw bar, 1, and an auxiliary or safety draw bar, 10, which are coupled, respectively, to the locomotive by a pin, 2, and to the tender by a pin, 4. It will, however, be obvious that it is similarly and equally applicable where, as in ordinary

practice, an auxiliary drawbar is not provided.

In the practice of my invention, referring descriptively to the specific embodiment which is herein illustrated, the drawbar pins, 2 and 4, are made without heads on their upper ends, and are turned down at and for a short distance from their lower ends, so as to form locking bearings, 2^b and 4^b, of reduced diameter, extending throughout such distance. Grooves, 3^a and 5^a, are formed transversely in the lower portions, 3^a and 5^b, of the foot plate, 3, of the locomotive, and of the drawbar pin casting of the tender, each of which provides a socket for one of the drawbar pins, said grooves 65 extending either in the direction of the longitudinal central planes of the two vehicles, as shown, or at an angle thereto, as preferred. A keeper, 11, which is in the form of a flat plate of metal, perforated to allow the locking bearing, 2^b or 4^b, of one of the drawbar pins, 2 and 4, to pass through it, and which has a short lip, 11^a, on one end, and a downwardly depending flange, 11^b, on the other end, is adapted to fit in 75 each of the grooves, 3^a and 5^a, of the castings, 3^a and 5^b, respectively, and to be secured removably thereto by a bolt, 12, (one or more) and nuts, 12^a. The keepers, 11, are fitted on the drawbar pins, 2 and 4, between the shoulders at the upper ends of the locking bearings, 2^b and 4^b, and keys, 13, which are driven through the pins below the keepers. Vertical movement, and resultant downward displacement, of the pins, 2 and 4, is consequently, effectually prevented, without interference with the ready insertion and removal of the pins, whenever required.

I claim as my invention and desire to secure by Letters Patent:

In a railroad vehicle, the combination with a part thereof having a socket for the reception of a headless drawbar pin having a reduced lower end, of means for retaining said pin in said socket, comprising a transversely grooved extension depending from said part, a keeper of less thickness than the

depth of said groove and adapted to be passed through the groove in said extension, said keeper having an aperture to receive the reduced end of the pin, a downwardly turned lip at one end, of such length as to permit its passing through said groove, and a downwardly turned flange at the other end, a bolt to secure said flange to said extension, and

means passing through said reduced end below said keeper to prevent upward movement of the pin. 10

HERMAN F. BALL.
